UNITED STATES PATENT OFFICE.

JOHN MERRY, OF NEW YORK, N. Y., ASSIGNOR TO THE BIGELOW CARPET COMPANY, OF MASSACHUSETTS.

DESIGN FOR A RUG.

SPECIFICATION forming part of Design No. 30,584, dated April 18, 1899.

Application filed March 22, 1899. Serial No. 710,104. Term of patent 31 years.

To all whom it may concern:

Be it known that I, JOHN MERRY, a subject of the Queen of Great Britain, and a resident of the city, county, and State of New York, have invented a new and original Design for Rugs, of which the following is a specification.

My design, as shown in the drawing, consists in a new design for a rug.

10 The design is composed of a middle portion and a border.

The middle portion is bounded by a stripe which constitutes the inner margin of the border and forms a rectangle containing bold ornamental corner-pieces, a bold central ornament, and ornamental figures projecting toward the central ornament from the middle of each side of the rectangle.

15 The border is composed of a main broad inner stripe and a narrower outer stripe, on both margins of each of which are narrower less

conspicuous stripes. The main broad stripe of the border is profusely ornamented with bold rug-like figuring of conventional flower and other pattern. The balance of the ornamented parts of the rug is plentifully decorated with less conspicuous rug-like ornamentation.

25 The drawing shows one-quarter of the design, the remaining three-quarters being in all respects facsimiles thereof.

What I claim, and desire to secure by Letters Patent, is—

30 The design for a rug substantially as shown and described.

35 In testimony whereof I have signed my name to this specification in the presence of two subscribing witnesses.

JOHN MERRY.
